SILENCER

Roy J. MacKenzie and Lucien L. Haas, Buffalo,
N. Y., assignors to Buffalo Pressed Steel Com-
pany, Buffalo, N. Y.

Application August 15, 1930. Serial No. 475,452

14 Claims. (Cl. 137—160)

This invention relates to silencers of the kind commonly employed for silencing the exhaust from an internal combustion engine.

The objects of this invention are to provide silencers of this type with pads of sound deadening material in certain portions thereof to improve the silencing effect; also to provide silencers of this kind including a plurality of shells forming chambers through which the gases pass in succession, and in which pads of sound absorbing material are used on portions of said shells to overcome the drumming effect produced by the impinging of gases on said shells; also to provide silencers of this kind, in which pads of sound absorbing material are provided in portions of the silencer opposite discharge passages in the shells to reduce noises resulting from the discharge of the gases; also to provide a silencer of this kind having an outer shell provided with a baffle intermediate of its end and having a pad of sound deadening material arranged against the side of said baffle opposite to that against which the incoming gases impinge; also to provide a silencer of this kind in which the baffle in the inner shell is apertured to permit a portion of the gases to pass through said pad; also to provide a silencer of this kind in which an intermediate shell is employed, a portion of which is of elliptical cross section and having pads of sound deadening material arranged in the portions of greater diameter of the elliptical shell; also to improve silencers of this kind in other respects hereinafter specified.

In the accompanying drawings:

Fig. 1 is a longitudinal central section of a silencer embodying this invention;

Figs. 2 and 3 are transverse sections thereof, on lines 2—2 and 3—3 respectively of Fig. 1;

Fig. 4 is a longitudinal central section of a silencer of modified construction;

Figs. 5 and 6 are sections thereof, respectively on lines 5—5 and 6—6 of Fig. 4.

This invention is applicable to silencers of many different constructions, and in order to illustrate our invention we have shown two different types of silencers provided with the improvements embodying our invention, and it will, of course, be understood that it is not intended to restrict this invention to the constructions shown.

In the construction shown in Fig. 1, the silencer includes an outer shell A and an inner shell B, both of these shells extending throughout the length of the silencer. A head C at the receiving end of the silencer provides shoulders to which the shells may be secured, this head being also

formed to provide a tubular extension c to which the exhaust pipe leading from the engine may be connected. At the opposite or discharge end of the silencer is arranged a head D to which the other ends of the shells are secured, and which is formed with a tubular extension d to which a tail or discharge pipe may be secured, or through which gases may be discharged directly to the air.

Between the ends of the inner shell, a baffle E is provided which may be suitably secured within the inner shell and which divides this shell into a gas receiving and a gas discharge chamber. This baffle is provided with perforations 10 and the inner shell is provided with additional perforations 11, through which gases pass out of the gas receiving chamber of the shell. We have found that a desirable silencing effect is produced by providing at the back face of the baffle E a cushion or pad of sound deadening material, and in the particular construction shown a pad F is provided. This pad may be made of any non-combustible pneumatic pressure equalizing substance, which has a large number of communicating air spaces therein, which act as pneumatic cushions to deaden the sound of the gases impinging against the baffle E. Metal wool has been found very desirable for this purpose, but it is not intended to limit this invention to this material, since asbestos in fibrous form, mineral wool, or other substances may be used in place of metal wool. The pad, in the particular construction shown, is arranged within a small cylinder 12 suitably secured or mounted in the discharge chamber of the inner shell, the cylinder shown being mounted on the baffle E and having its other end closed by means of a cap or disk 14. The cylinder 12 is preferably provided with apertures 15, and consequently a small portion of the gases entering the receiving chamber pass through the perforations 10 of the baffle and through the pad F and perforations 15 directly into the discharge chamber of the silencer. It is not, however, necessary to provide for a passage of the gases through the pad F, since if the cylinder 12 were imperforate, a similar silencing effect would be produced.

The space between the inner and outer shells A and B is divided by an annular partition or baffle G, the inner and outer edges of which are respectively secured to the shelves B and A. The baffle or partition G has apertures 17 therein through which the gases may pass into a chamber 18, from which they pass through holes 19 in the

inner shell B to enter into the discharge chamber in this shell.

The space between the partition or baffle G and the head C is, in the construction shown, 5 divided into two silencing chambers by means of a tapering shell H, the smaller end of which engages the inner shell B and is suitably secured to the head C. The larger end of this shell is secured to a shoulder 20 of the baffle or partition 10 G, and preferably this shoulder is elliptical in form, so that the larger end of the shell H is of elliptical cross section.

A material reduction in the noise of the exhaust can be effected if the gas is discharged from the 15 receiving chamber into the next adjacent chamber against pads or pneumatic pressure equalizing substances, and by making a portion of the intermediate shell elliptical, such pads can be located in the wider portions of the shell where they will 20 produce the least restriction of the passages for the gas.

In the construction illustrated, therefore, we have provided pads I, which are arranged in those 25 portions of the shell H which are adjacent to the ends of the elliptical cross section through which the greatest diameter passes, and the discharge openings 11 in the inner shell B are so arranged that the gases discharged therethrough impinge against these pads. By means of the arrangement 30 described, the pads produce the silencing effect upon the gases which would otherwise be discharged against the shell H, and by arranging these pads in the ends of the elliptical cross section, the portion of the chamber 21 into which 35 these gases discharge from the receiving chamber of the inner shell is not materially reduced in cross section, so that no material increase in back pressure results. The pads I may be of the same or similar material as the pad F, and the 40 material is confined in its correct position by means of two plates 23 of perforated metal, which plates may be suitably spot welded, or otherwise secured to the shell H. By means of the arrangement described, an economic use is made of the 45 sound deadening material which results not only in a saving of material, but enables these pads to be used in the silencer without increasing the size thereof, and without restricting the gas passages of the chamber 21.

50 The gases are discharged from the chamber 21 through a series of apertures 25 arranged in the portion of the shell beyond the pads I. The gases, after passing through the apertures 25, enter into a chamber 26, from where they 55 can pass through the apertures 17 in the baffle or partition G, and consequently pass out of the silencer, as already described.

We have found that in silencers some noises 60 commonly called "drumming" result from the impinging of jets or streams of gas against an outer shell of the muffler or silencer. We have also found that this drumming effect can be eliminated or reduced so as to render it unobjectionable by the use of a pad or lining of 65 sound deadening material arranged within these shells, so that the radially discharged gases impinge upon these pads or linings. In order to prevent this drumming and to further reduce noises of the exhaust, another pad or lining K 70 of suitable sound absorbing material is provided adjacent to the inner wall of the outer shell A and adjacent to the discharge apertures 25 in the shell H. This pad K may be cylindrical in form and fits snugly against the inner wall of 75 the shell A, and is preferably held in place by

means of a shell 27 of perforated material. Preferably, this shell 27 is also tapered or frustoconical in form so as to extend approximately parallel to the shell H. This arrangement provides a practically uniform space for the gases 80 between the pad or lining K and the shell H, and also provides for an increased thickness of the pad adjacent to the baffle C, so that drumming effect against this baffle is also prevented. By lining only that portion of the outer shell against 85 which gases impinge with the sound-deadening material, the gas passages within the silencer are not materially restricted, and a considerable portion of the outer shell contacts directly with the gases, resulting in a more rapid cooling of the 90 same.

In the case of both of the pads I and K, in addition to eliminating or materially reducing the usual drumming effect, a material silencing of the noises of the exhaust is effected by the provision of these pads, preferably due to a certain amount of pressure equalizing effect produced by the pads, permitting gases to flow into the air spaces in these pads when a sudden flow of gas enters the silencer, and then again permitting this gas to discharge out of the air spaces in the pads between explosions or gas discharges. It will be noted that this same silencing effect is produced by means of the pad F, which is arranged in such a manner that the gases discharging 100 from the chamber 18 through the apertures 19, impinge against the perforated cylinder 12 in which the pad F is arranged.

Holes or openings 28 in the inner shell near the receiving end thereof serve to prevent damage to the silencer in case of explosions within the muffler and permit a small flow of gas in the chamber 21 in a direction contrary to the main flow of gas.

In the construction shown in Figs. 4 to 6 inclusive, outer and inner shells A¹ and B¹ are secured at their ends to heads C¹ and D¹, in the manner described in connection with Figs. 1 to 3, and a baffle E¹ is provided, which divides the inner shell into a receiving and discharge chamber. A pad F¹ in rear of the baffle E¹ and made of suitable sound deadening material is, in this construction, confined in a chamber in the inner shell arranged between the baffle E¹ and a second baffle 30. The baffle E¹ contains perforations 115 through which a portion of the gases entering the receiving chamber may pass to the pad F¹, and the sides of the shell B¹, which confine this pad, are provided with apertures through which some of the gases entering the pad may pass. The head 30 is also provided with apertures 120 through which some of the gas which has passed through the pad F¹ may enter directly into the discharge chamber of the silencer.

The portion of the inner shell which encloses 125 the gas receiving chamber is provided with apertures 33, through which most of the gases discharge against the pad or lining K¹ upon entering the chamber between the inner and the outer shell, the pad K¹ being confined in its operative position by means of a cylinder 34 of perforated metal, and by means of an annular end wall 35 suitably secured to the outer shell.

The space between the inner and outer shells 130 of this silencer is divided into two chambers by means of an annular partition or baffle G¹ having discharge apertures 36 therein. This annular baffle or partition G¹ also is of shouldered form, and the space at the discharge side of this baffle 135 or partition is divided into two chambers, by

means of a tapering partition 38, one end of which engages a shoulder 39 on the partition G¹, and the smaller end of which engages the inner shell B¹ and may be secured to a shoulder on 5 the head D¹. The apertures 36 in the partition G¹ discharge gases into a chamber 40 between the tapered shell 38 and the outer shell A¹. Holes 41 in the shell 38 cause gases to flow into the chamber 42 between the shells 38 and B¹, and 10 holes 43 in the shell B¹ admit gases to the discharge chamber within this shell, from where they are discharged from the silencer.

15 Silencers embodying this invention as illustrated in both structures shown, are so constructed that they are not solely dependent upon the action of the pneumatic pressure equalizing substance to be useful, since sufficient muffling chambers are provided to ensure a fairly satisfactory muffling effect even if the metal wool or 20 other material becomes burned out or filled with soot or carbon.

We claim as our invention:

25 1. A silencer including an outer shell, a shell arranged within said outer shell and forming therewith a passage for gases and having discharge openings therethrough through which gases discharge outwardly toward said outer shell for flowing in said passage, and a layer of metal wool arranged adjacent to that portion of the 30 inner surface of said outer shell toward which said gases are discharged and into which a portion of said gases may penetrate, and a shell of perforated metal confining said metal wool between said last mentioned perforated shell and 35 said outer shell.

40 2. A silencer including outer and inner cylindrical shells forming between them a passage for gases, said inner shell being arranged to receive incoming gases at one end thereof and having a perforated baffle intermediate of its ends against which incoming gases impinge, a cushion of non-combustible fiber-like material arranged 45 on the side of said baffle opposite to that on which incoming gases impinge, and which has a silencing effect on said gases and permits a portion thereof to pass therethrough, and openings in 50 said inner shell through which the remainder of the gases are discharged therefrom into said passage and from said passage into said inner shell beyond said cushion.

55 3. A silencer including an inner and an outer shell, a baffle arranged intermediate of the ends of said inner shell and dividing the same into a gas receiving and a gas discharge chamber, a pad of non-combustible fiber-like material in 60 said discharge chamber adjacent to said baffle, said baffle having perforations in the portion thereof adjacent to said pad to permit a portion of the incoming gases to discharge through said pad, and openings in said inner shell at both 65 sides of said baffle to permit the remaining gases to flow out of the receiving chamber of said inner shell and into the discharge chamber thereof.

70 4. A silencer including an inner and an outer shell arranged to form between them a space for gas, a baffle arranged intermediate of the ends of said inner shell and dividing the same into a gas receiving and a gas discharge chamber, a 75 pad of non-combustible fiber-like material in said discharge chamber adjacent to said baffle, said baffle having perforations in the portion thereof adjacent to said pad to cause said pad to produce a silencing effect on said incoming gases, and openings in said inner shell at opposite sides

of said baffle to permit gases to flow outwardly from the receiving chamber of said inner shell into said space between said inner and outer shells, and then into the discharge chamber of said inner shell.

80 5. A silencer having inner and outer shells arranged to form between them a space for gas, a baffle intermediate of the ends of said inner shell to divide the inner shell into a receiving chamber and a discharge chamber, said baffle having perforations therethrough, a pad of sound absorbing non-combustible material arranged on the discharge side of said baffle, openings in said inner shell at both sides of said baffle to permit gases to discharge outwardly from said receiving chamber into said space between said inner and outer shells, and then into said discharge chamber, and a pad of non-combustible sound absorbing material arranged about and spaced from the portion of the inner shell from which gases are discharged outwardly, to cause said gases to impinge against said last mentioned pad.

85 6. A silencer having inner and outer shells arranged to form between them a space for gas, a baffle intermediate of the ends of said inner shell to divide the inner shell into a receiving chamber and a discharge chamber, said baffle having perforations therethrough, a pad of sound absorbing non-combustible material arranged on the discharge side of said baffle, openings in said 90 inner shell at both sides of said baffle to permit gases to discharge outwardly from said receiving chamber into said space between said inner and outer shells, and then into said discharge chamber, a pad of non-combustible sound absorbing material arranged about and spaced from the portion of the inner shell from which gases are discharged outwardly, to cause said gases to impinge against said last mentioned pad.

95 7. A silencer including a shell, a second shell arranged about said first shell and having a portion thereof spaced at a greater distance from said inner shell than other parts thereof, a pad of sound absorbing material in said spaced portion, and discharge openings in the inner shell arranged to direct jets of gases toward said pad.

100 8. A silencer including a shell, a second shell arranged about said first shell and having a portion thereof of substantially elliptical cross section, a pad of sound absorbing material in a portion of greater diameter of said elliptical portion, and gas discharge orifices in the inner shell arranged to direct gas jets toward said pad.

105 9. A silencer including inner and outer substantially cylindrical shells, an intermediate tapering shell arranged between the inner and outer shells, a pad of sound absorbing material in the portion of said intermediate shell of greater diameter, a pad of sound absorbing material arranged on said outer shell opposite the portion of lesser diameter of said intermediate shell, and discharge apertures in said inner and intermediate shells arranged to deflect gases discharged therethrough against said pads.

110 10. A silencer including an inner and an outer shell arranged to form between them a space for gas, a baffle arranged intermediate of the ends of said inner shell and dividing the same into a gas receiving and a gas discharge chamber, a pad of sound absorbing material arranged against said

- 10 11. A silencer including an inner and an outer shell arranged to form between them a space for gas, a baffle arranged intermediate of the ends of said inner shell and dividing the same into a gas receiving and a gas discharge chamber, a pad of sound absorbing material arranged against said baffle at the side thereof opposite to the inlet of the silencer, to silence gases impinging against said baffle, and openings in said inner shell at said receiving and discharge chambers thereof 15 to permit gases to flow from said receiving chamber into said space between said shells and from said space into said discharge chamber, the openings leading into said discharge chamber being arranged to cause gases to impinge against said pad, said baffle having openings arranged to permit a restricted quantity of said gases to flow through said pad directly into said discharge chamber. 20
12. A silencer including inner and outer shells arranged to form between them a space for gas, a baffle arranged intermediate of the ends of said inner shell and dividing the same into a gas receiving and a gas discharge chamber, a pad of sound absorbing material arranged within said inner shell at the discharge side of said baffle, said baffle having perforations therein in the portion thereof adjacent to said pad, said inner shell having discharge openings for permitting gas to discharge from said receiving chamber 25
